METHOD AND APPARATUS FOR DISPENSING
GAS MATERIALGeorge H. Zenner, Kenmore, N. Y., assignor to
The Linde Air Products Company, a corporation
of Ohio

Application August 7, 1937, Serial No. 157,876

14 Claims. (Cl. 62—1)

This invention relates to a method of and apparatus for dispensing gases stored in the liquefied state and more particularly to a method of and apparatus for supplying auxiliary oxygen for high altitude flying.

Among the objects of the invention are to provide a method of and apparatus for dispensing gas which insure rapid pressure building; insure adequate flow being quickly attained; decrease the heat influx to the liquefied gas container during periods of idleness; supply heat for pressure building in proportion to the flow of gas; and maintain constant gauge pressure independent of the rate of withdrawal and of fluctuations of atmospheric pressure caused by changes in altitude; and, further, to provide a simplified, rugged, easily disassembled gas dispensing apparatus of high unit capacity per unit of weight.

These and other objects of the invention will in part be obvious and in part become apparent from a consideration of the following description in combination with the accompanying drawings, in which:

Fig. 1 is a simplified flow diagram showing the general principle of operation of the invention;

Fig. 2 is a view, partly in section, of one form of apparatus according to the invention;

Fig. 3 is a longitudinal section of a flow control valve which may be used with any of the various forms of apparatus according to the invention;

Fig. 4 is a transverse section of a modified form of apparatus according to the invention taken on line 4—4 of Fig. 5;

Fig. 5 is a plan view, partly in section, of the apparatus shown in Fig. 4; and

Fig. 6 is a view, partly in section, of a further modified form of apparatus according to the invention.

For an understanding of the general method of operation of the apparatus according to the invention, reference may be had to the schematic flow diagram of Fig. 1. In this figure is shown a vacuum bottle or container 10, disposed in an outer casing or support 12, which has disposed thereon a steam chest, or other equivalent heating means, 14. The container 10 is partially filled with liquefied gas through a suitable filler opening, not shown. After filling, the container 10 is sealed and a flow control valve 16 opened the desired amount.

As soon as a slight pressure difference between the delivery side of the valve 16 and the interior of the container 10 has been created by

heat leakage into the container 10, or by an increase in elevation of the container, as when used to supply oxygen for high altitude flying, liquefied gas flows through a liquid withdrawal line 18 from which it passes to a liquid vaporizer and superheating coil 20 located in the steam chest, or other heating means 14, where it is vaporized and the vapor superheated to any desired temperature, for example, approximately 5 atmospheric temperature. The resultant vapor then passes through a heated vapor return line 22 to a suitable heat exchanging means 24 where it gives up a portion of its heat, vaporizing some of the liquefied gas in container 10 and thereby 10 building pressure in the gas phase above the liquefied gas in container 10. The cooled vapor then passes through a vapor withdrawal line 26 to a reheat coil 28, where it is again warmed, and from which it passes through a conduit 30 to the flow control valve 16.

Simultaneously the gas above the liquid in container 10 may be withdrawn through conduit 32 from which it passes through a gas heating coil 34 and a heated gas phase withdrawal line 25 or connection 36 to a pressure regulator 30. Connected in the heated gas phase withdrawal line 36 are a safety valve 38 and a vent valve 40. When the gas has attained a predetermined pressure, it passes through the pressure regulator 30 and the conduit 31 to the flow control valve 16.

One form of apparatus operating in accordance with the above described general method of the invention is shown in Figs. 2 and 3, and includes a container 10 having an inner wall 42 and an outer wall 44, the space between the same being evacuated. The inner wall 42 is provided with an inwardly extending recess 46 which is filled with absorptive silica gel, or other suitable gas absorbing material, 48, for maintaining the efficiency of the vacuum in the space between the walls 42 and 44. Concentric inner and outer tubular members 49 and 50 are secured respectively to the inner wall 42 and the outer wall 44 to form a neck 51 for the container 10. The container 10 may be supported in any desired manner, such as by an outer casing or a supporting cradle. For illustrative purposes only, the container 10 is shown as supported on a casing 12 by a bearing member 52 secured to the neck 51 of the container 10 and engaging a bearing member 54 mounted in a tubular extension 56 of the casing 12.

A tubular member or sleeve 66 extends through the bearing member 52 into container 10, and 55 is secured in a gas-tight manner to a closure

plug 67 which is secured to bearing member 52 by a collar 68, engaging a shoulder 70 on the plug 67 and threaded on the bearing member 52. Sleeve 66 terminates approximately at the center of container 10 and has no connection with gas space 76.

Extending centrally through sleeve 66 is liquid withdrawal line 18. Line 18 extends through the plug 67 to a steam chest, or other heating means 14, where it is joined to heated vapor return line 22, which passes through the plug 67 and sleeve 66 to a heat exchanging coil 72. The heating means 14 may comprise a heating chamber having inlet and outlet openings 73 and 75, respectively, for heating fluid, or may be a fin heater in which material from either the liquid or gas phase is relatively heated by a blast of air from a fan or blower, or by the exhaust gas discharged by the airplane motor.

Connected to heat exchanging coil 72 is vapor withdrawal line 26 which passes through sleeve 66 and the plug 67 to the heater 14 from which it leads through conduit 31 to a regulator block 74 shown in detail in Fig. 3. Also extending through sleeve 66 and plug 67 is the gas phase withdrawal conduit 32 which at one end has a bent portion 33 terminating at an opening in sleeve 66 and secured gas-tightly in said opening. The conduit 32 thus communicates with the space 76 above the liquefied gas in the container 10, and at its other end is connected to a goose neck or return bend 35 communicating with the gas heating coil 34 which is connected to the regulator block 74 through connection 36.

The regulator block 74, shown in Fig. 3, has an inlet passage 78, an inlet passage 80, of considerably smaller diameter than the inlet passage 78, and an outlet passage 82 therein. Disposed in the passage 82 is a flow regulator valve 84 connected to an indicating handle 86, which is used to predetermine the rate of gas dispensation. Connected to passage 78 are safety valve 88 and vent valve 40. Connection 36 and line 31 are connected, respectively, to passages 78 and 80 in block 74. The passage 80 may be provided with a restricted orifice 87 for a purpose described hereinafter.

Passage 78 and passage 80 terminate respectively in passages 88 and 89 which lead to one side of a diaphragm 90 forming part of a back pressure valve 92, which valve also comprises a cavity 94 open to the immediate atmosphere and a spring 96 engaging at one end a spring seat secured to diaphragm 90 and at its opposite end a spring seat engaged by a pressure adjusting screw 98. The diaphragm 90 is thus responsive to the difference between pressure in the container and the immediate atmospheric pressure and, as will be apparent from the following description of the operation of the means 14, acts as a single means operating to effect discharge of gas from the gas space 76 when the pressure difference exceeds a predetermined value and to insure preferential withdrawal of gas from the gas space.

The operation of the above described embodiment of the invention follows the general principles demonstrated in connection with the flow sheet shown in Fig. 1. Operating handle 86 is first set to open valve 84 the desired amount to permit the proper flow of gas from the apparatus. When a slight difference of pressure exists between the interior of the container 10 and the consuming device, liquid oxygen passes through the liquid withdrawal line 18 to the

heater 14 where it is vaporized and the resultant vapor is superheated. The superheated vapor is returned through heated vapor return line 22 to the coil 72 and passing therethrough warms and vaporizes a portion of the liquid surrounding said coil. From the opposite end of coil 72, the cooled vapor passes through the vapor withdrawal line 26 to the heater 14, where it is re-heated, and from there passes through line 31 to the regulator block 74. In flowing through the regulator block 74, the superheated vapor passes through the restricted orifice 87 into the passages 88 and 89 and, under certain conditions, will flow through the passage 82 and past the valve 84 to the consuming device or atmosphere.

The heat given up by the superheated vapor as it passes through the coil 72 vaporizes some of the liquid in the container 10, thereby causing an increase in the pressure of the gas phase accumulated in the space 76 above the liquid level in the said container. When this pressure has reached a certain predetermined value, material from the gas phase will pass through the conduit 32, through the heater 14 and through connection 36 into the passage 78 in the regulator block 74. The vent valve 40 may be used to discharge gas from passage 78 during idle periods and the safety valve 88 automatically relieves the gas pressure when the same becomes excessive (as it may do when the valve 84 is closed) because of natural heat leakage into the container. When the material from the gas phase has reached a sufficient pressure, as predetermined by adjustment of the screw 98, the diaphragm 90 will lift, and the gas material will pass from the passage 78 into the passage 89 and thence through the passage 82 past the valve 84 to the consuming device or atmosphere. The discharge from the regulator block 74 is taken preferentially from the gas space 76 in container 10 when the pressure exceeds the value for which valve 82 is set. For this purpose passage 78, withdrawal line 32 and connection 36 are made of much larger diameter than the passage 80, line 31, withdrawal line 26, return line 22 and liquid withdrawal line 18. If desired or necessary, the passage 80 may further be provided with the aforementioned restricted orifice 87. However, in practice this orifice is not usually necessary since the restriction of the long tortuous withdrawal system, 18, 22, 72, and 80, for material from the liquid phase is in itself sufficient to insure preferential withdrawal of material from gas space 76 through the withdrawal system 32, 35, 36, and 78.

With the above described arrangement, when diaphragm 90 is lifted the respective pressures in the passage 80 and the space 76 will be substantially equal and balanced. Thus, there will be no pressure difference available to cause material from the liquid phase in the container 10 to flow to the regulator block 74. However, with the diaphragm 90 lifted, gas will flow from the space 76 to the regulator block. Hence, preferential withdrawal of gas from space 76 is assured when the diaphragm 90 is lifted.

The flow of gas from the space 76 reduces the pressure in this space, thus tending to permit the diaphragm 90 to be forced by the spring 96 to a closed position. On the other hand, withdrawal of material from the liquid phase tends to increase the pressure in space 76 thus causing the diaphragm 90 to lift. By proper adjustment of the compression of spring 96 by the screw 98,

the withdrawals from each phase will be balanced so that the pressure in space 76 remains at a desired fixed value as determined by the setting of the screw 92. This causes constant gauge pressure to be maintained within the container. The term "constant gauge pressure" means that a fixed differential pressure is maintained from inside the container to the atmosphere, regardless of variations in atmospheric pressure as with altitude. Thus, at 28,000 feet altitude the barometric pressure is only 247 mm. of mercury as compared with 760 mm. of mercury at sea level. This reduced atmospheric pressure affects the back pressure regulator 92, safety valve 38 and a pressure gauge, not shown, in the same manner, so that the differential pressure between the container and atmosphere is measured and maintained. This is called "gauge" pressure.

The maintenance of constant gauge pressure within the container 10 produces a rate of flow through withdrawal valve 84 which remains nearly constant regardless of changes in altitude. Furthermore, with a constant gauge pressure maintained in the space 76, a much simpler flow control may be used than with a fluctuating pressure.

With the sleeve 66 terminating at approximately the center of the container 10, the container may be placed in inverted position when it is 50 percent or less full without the pressure building up excessively. This may be of considerable advantage in aircraft installations.

Another important advantage of the above described apparatus is that it provides for rapid pressure building so that adequate flow can be quickly attained without the liquefied gas container being susceptible to a correspondingly high heat leak during periods of idleness. The heat supplied for pressure building is proportional to the flow determined by the flow control valve 84. The arrangement for maintaining constant gauge pressure in the apparatus is relatively simple and insures that such constant gauge pressure is maintained at all times regardless of external atmospheric pressure on the container.

Due to its gas-tight connection with the closure plug 67, the sleeve 66 is in communication with the interior of the container 10 only at its lower end which is immersed in the liquid in the said container. There is no connection between the gas space 76 of the container 10 and the interior of the sleeve 66. Thus, the sleeve 66, being closed at its upper end, acts as a gas collecting bell whereby the air or other gas remains in the sleeve 66 when it is inserted into the container 10 and prevents the liquid in the container 10 from rising more than a slight distance in the interior of the sleeve 66. The liquid in the container 10 is therefore only in contact with a limited portion of the various conduits leading to the exterior of the apparatus. Thus the heat loss into the container 10 is materially reduced during idle periods because of this limited area of contact between the liquid and any heat conducting member which may lead to the exterior of the apparatus. Furthermore, all tubes passing from the cap 67 to the liquid in the container 10 are made of metals having the lowest possible thermal conductivity in order to keep normal evaporation at a minimum. Suitable metals which may be used for these tubes are nickel silver "Everdur" (3% silicon, 1% manganese, 96% copper) or stainless steel (18% chromium, 8% nickel, balance iron). The above metals are given by way of example as,

obviously, other metals of low thermal conductivity may be used.

As will be noted from Fig. 2, the pressure generating apparatus, that is, the various conduits 5 and the heating coils 12, are all disposed within the confines of the sleeve 66. This permits the sleeve 66 and the pressure generating apparatus to be removed from the container as a unit by first loosening the collar 68 and then withdrawing the sleeve 66 and the pressure generating apparatus. Thus one pressure generating apparatus may be used for several containers. This is important in airplane use particularly, as a plurality of containers of liquid oxygen may be stored in the airplane and the single pressure generating apparatus used with each container of oxygen consecutively. Not only does such a procedure save valuable weight and space on the airplane but it also permits of greater economy of operation first because a single pressure generating apparatus can be used with several containers and second because there are no external connections on the reserve containers which would afford an opportunity for heat leakage thereinto while they remain in the idle state.

A modified form of apparatus embodying the invention is shown in Figs. 4 and 5. In this form of the invention an outer supporting casing 100 is provided which supports a vacuum bottle 102 constructed similarly to that shown in Fig. 2 of the drawings. The outer casing is provided with a vertical tubular extension 104, to the upper end of which is secured a collar 106 having a threaded aperture 108 therein. In the threaded aperture 108 is threadedly secured a tubular member 110 which forms a part of the vacuum bottle 102. Member 110 extends completely through collar 106 and has threadedly secured to its upper end a second tubular member 112 having a circumferential rib 114 thereon; to which rib is secured, by bolts or other suitable means, a flat ring 116 which supports an annular heating chest 118. A suitable heat insulating washer 119 is placed between ring 116 and heating chest 118 to insure a minimum of heat conduction from the heating chest to the neck 110. Heating chest 118 is provided with heating fluid inlet 120 and heating fluid outlet 122, and disposed therein are three separate heating coils 124, 126, and 128 for purposes to be later described. Secured to the member 112 is a threaded tubular member 130 which is provided at its upper portion with a semi-circumferential rib 132 to which is secured the inner edge of a protecting cover 134 which, at its outer edge, is secured to the flat ring 116. Suitable packing means are provided at each end of tubular member 130. Closing the end of tubular member 130 is a plug 136 having an aperture 138 therein in which is threadedly secured a pressure gauge 140. Supported upon the flat ring 116 is a flow regulating device 142 including a back pressure regulating valve 144 of the same type as the valve 92 shown in Fig. 3.

The internal arrangement of vacuum bottle 102 is generally similar to that of the vacuum bottle shown in Fig. 2 of the drawings except that the sleeve 66 and the conduit 32, for withdrawal of material from the gas phase are eliminated and this gas material is allowed to enter the space 146 within the neck of the bottle 102. A liquid withdrawal line 148 extends through an opening in the tubular member 130 and a second opening in the ring 116 to one end of the coil 124 disposed in the heating chest 118. A

heated vapor return line 150 is connected to the other end of the coil 124 and extends through the ring 116 and the tubular member 120 to the interior of the vacuum bottle 102, where it is connected to one end of a heat exchanging coil which may be similar to the heating coil 72 of Fig. 2, or may resemble the heat exchanging device 24 of Fig. 1. To the opposite end of this coil is connected a vapor withdrawal line 152 which extends through the tubular member 130 and the ring 116 to one end of the second coil 126 in the heating chest 118. From the opposite end of the heating coil 126, a conduit 154 extends to the flow regulating device 142. Gas is withdrawn from the interior space 146 of the neck of the vacuum bottle 102 through an opening 156 (see Fig. 5) to a conduit 158 which extends to one end of the third coil 128 disposed in the heating chest 118. From the other end of coil 128 a conduit 160 extends to the flow regulating device 142.

Connected to conduit 160 are a safety valve 170 and a vent valve 162 which latter controls a vent 164. The flow regulating device 142 is provided with a valve 166 for controlling the flow through a withdrawal line 168.

In operation, steam or other heating fluid is passed through the inlet 120 into the heating chest 118 and out through the outlet 122. When a difference of pressure has been created between the interior of the vacuum bottle 102 and the consuming apparatus, due to the reduction of atmospheric pressure or heat leakage into the bottle 102, liquefied gas is withdrawn through the liquid withdrawal line 148, is passed through the heating coil 124, where it is vaporized and the resultant vapor superheated, which latter is then returned through the heated vapor return line 150 to the heat exchanging means in the vacuum bottle 102 wherein it gives up some of its heat to the surrounding liquid. It then passes through the vapor withdrawal line 152 to the second heating coil 126 where it is again heated and from which it passes through the conduit 154 to the flow regulating device 142. When sufficient pressure has been built up above the liquefied gas in the vacuum bottle 102, gas is withdrawn through the conduit 158 to the heating coil 128 and thence to the conduit 160 from which it is delivered to the flow regulating device 142. The operation of the flow regulating device 142 is similar to that of the regulator block 74 described in connection with Fig. 3.

As the heating means 118 is mounted on and closely surrounds the upper portion of the support for the liquid container, a very compact arrangement is provided which permits the whole apparatus as a unit to be moved from place to place with great facility and to require only a limited amount of space. It should be noted that the mounting of the heating apparatus utilizes available space around the neck of the container without increasing the overall horizontal dimensions of the container. The apparatus described above can likewise be very quickly disassembled for repair and replacement. Furthermore, by loosening the tubular member 112 the heating means and the pressure generating means may be removed as a unit from the liquid container, thereby providing the same advantages as the modification described in Fig. 2, namely, the use of a plurality of liquid containers and the avoidance of unnecessary heat loss when the containers are stored in the idle condition.

Fig. 6 represents a modified form of the apparatus shown in Fig. 2, in which only a relatively small portion of the liquid in the container is heated and the main body of liquid is not disturbed, thereby allowing non-equilibrium pressure building and providing for low heat leakage losses during periods of idleness. In this modification a container 10' is provided with a sleeve 66' similar to the sleeve 66 of Fig. 2 but extending into the container to a point adjacent the lower end of the heat exchanging coil 72'. A liquid withdrawal line 18' is disposed within the sleeve 66' and also disposed therewithin are a heated vapor return line 22' and a vapor withdrawal line 26'; respectively connected to opposite ends of the heat exchanging coil 72'. A gas phase withdrawal conduit 32' extends into the sleeve 66' and terminates a short distance below the top portion of the container 10', extending through the wall of sleeve 66' with a gas-tight fit and opening into the space above the liquid in container 10'. A vent tube 180 extends from a point spaced above the heating coil 72' to an opening 182 in the sleeve 66' located above the level of the liquid in the container 10'.

The operation of this modified apparatus is generally similar to the operation of the apparatus shown in Fig. 2. The sleeve 66' encloses a small vertically extending column or core of liquid within its lower end, and this liquid may rise within the sleeve 66' until it contacts with the lower end of the vent tube 180. This vent tube is provided in order to assure that liquid will rise within the sleeve 66' to a certain extent in spite of the fact that the sleeve 66' acts as a gas bell as explained in connection with Fig. 2. The liquid is permitted to rise in the sleeve 66' to a point above the heating coil 72'. It then seals the end of the vent tube 180 and is thereby prevented from rising further within the sleeve. Liquid is withdrawn through the liquid withdrawal line 18', heated and vaporized, and the vapor is superheated and then returned through the heated vapor return line 22' to the coil 72' where it gives up some of its heat to the liquid surrounding the coil. The vapor, now somewhat cooled, is then withdrawn through the vapor withdrawal line 26' and reheated in the same manner as previously explained. The heat given up in the coil 72' heats and vaporizes that portion of the liquid disposed within the lower end of the sleeve 66' thereby causing a rise in the pressure of the gas above the liquid in the sleeve. The gas produced by vaporization in sleeve 66' forces the liquid level in the sleeve to a point below the end of vent tube 180 and the gas flows through this tube into the space above the liquid in container 10' from which this gas is then discharged through the gas phase withdrawal conduit 32' and to a flow regulator similar to those previously described.

If desired, the sleeve 66' might be supported at its lower end on the heating coil 72' and be terminated a short distance above the level of the liquid in the container 10'. The vent tube 180 can then be eliminated while the advantage of non-equilibrium pressure building can still be obtained. In this instance, however, the liquid phase will rise in the sleeve 66' to the level of the main body of liquid phase. The same effect can be obtained by disposing a second vent opening in the sleeve 66' above the level of the liquid in the container 10', or by employing, in the embodiment shown in Fig. 4, a sleeve supported at its lower end on the heating coil and terminating

a short distance above the level of the liquid in the container.

With any of the above described modifications of the apparatus shown in Fig. 6, rapid pressure-building is produced while avoiding turbulence in the main body of liquid outside the sleeve 66'. Only the top layer of liquid outside this sleeve will be heated, as by condensation of gas on the surface. The returning heated vapor passing through the heating coil 72' heats only that portion of the liquid which is contained within the sleeve 66', thereby avoiding heating of the main body of the liquid. Due to the presence of gas phase in the sleeve 66' above the level of the liquid therein, a heat insulating effect is obtained which prevents transmission of heat to the main body of liquid. At the same time, because the main body of liquid is not heated during utilization of the apparatus, there is less subsequent loss of gas phase by evaporation. Furthermore, because of the insulating layer of gas along the inside of the sleeve 66', there is little transmission of heat from the apparatus which extends to the outside of the liquid in the container 10' during idle periods. As in the apparatus shown in Fig. 2, the entire pressure-building arrangement can be withdrawn through the neck of the vacuum bottle, and accordingly only one pressure-building apparatus is needed for a number of liquid containers, and during periods of idleness there are no external connections to the liquid containers allowing heat to enter thereinto and cause a loss of vapor therefrom. Obviously, any one of the modifications of the apparatus shown in Fig. 6 can be substituted for the pressure generating means shown in Fig. 2.

If the lower end of the sleeve 66' is supported on the heating coil 72' and the sleeve is terminated just above the level of the liquid in the container, it will no longer act as a gas collecting bell but will still permit of heating only the small core of liquid contained therein and not heating the main body of liquid in the container 10'.

This is also true of this construction when a vent is added in the sleeve 66' above the liquid level in the main container. Both of these latter expedients will likewise result in low heat leak into the container 10' and low heat loss during operation as described above.

Although several embodiments of the invention are disclosed in detail, it will be evident that numerous changes may be made in such details without departing from the principles of the invention.

What is claimed is:

1. A liquefied gas container; a heating coil disposed in said container; a tubular extension connected to said container; a tubular member disposed concentrically of said tubular extension and extending into said container; said heating coil being aligned with said tubular member; a gas phase withdrawal conduit disposed in said tubular member; a means for maintaining the level of liquid within said tubular member above said heating coil.

2. A liquefied gas container; a heating coil disposed in said container; a tubular extension connected to said container; a tubular member disposed concentrically of said tubular extension and extending into said container; said heating coil being aligned with said tubular member; a gas phase withdrawal conduit disposed in said tubular member and communicating with the space above the liquid in said container; and

means for maintaining the level of liquid within said tubular member at a desired point below the level of liquid in the container.

3. Gas dispensing apparatus including a container for liquefied gas having a tubular extension thereon; a support for said container surrounding the same and having a tubular extension thereon concentric with and disposed externally of said first mentioned tubular extension; a heating chamber surrounding said second-named tubular extension and supported thereby; a plurality of heating coils disposed in said heating chambers; conduits connecting certain of said coils with said container; and other conduits connecting certain of said coils with a flow regulating device.

4. Gas dispensing apparatus including a container for liquefied gas and a tubular extension attached thereto; a heating chamber concentric with and supported by said tubular extension; a flow regulating device also supported by said tubular extension; a plurality of heating coils disposed in said heating chamber; a liquid withdrawal conduit and a heated vapor return conduit disposed in said container and connected to opposite ends of one of said coils; a cooled vapor withdrawal conduit disposed in said container and connected to one end of another of said coils; a gas phase withdrawal conduit in communication with said tubular extension and connected to a third of said heating coils; and conduits leading respectively from each of said second and third heating coils to said flow regulating device.

5. Gas dispensing apparatus including a container for liquefied gas, a heating means disposed adjacent said container; a liquid withdrawal conduit, a heated vapor return conduit, a cooled vapor withdrawal conduit, and a gas phase withdrawal conduit, extending between said container and said heating means; a heating coil disposed in said container, the opposite ends of which are connected respectively to said heated vapor return conduit and said cooled vapor withdrawal conduit; and a sleeve surrounding said liquid withdrawal conduit, said heated vapor return conduit, and said cooled vapor withdrawal conduit, said sleeve extending at least half-way into said container and terminating at its lower end above said heating coil.

6. In gas dispensing apparatus, a container for liquefied gas; a tubular extension connected thereto; a tubular member disposed concentrically of said tubular extension and extending into said container at least half-way; liquid withdrawal, heated vapor return, cooled vapor withdrawal, and gas phase withdrawal conduits disposed inside of said tubular member; a heating coil disposed in said container below the end of said tubular member and having its end portions connected respectively to said heated vapor return and said cooled vapor withdrawal conduits; said liquid withdrawal and gas phase withdrawal conduits extending from said tubular extension to heating means, and said gas phase withdrawal conduit having a gooseneck portion therein.

7. In gas dispensing apparatus a container for liquefied gas having a gas space therein above the liquid; means for withdrawing liquefied gas from said container; means for vaporizing said liquefied gas and superheating the vapor produced; a unitary flow regulating means; a conduit for conducting said superheated vapor to said flow regulating means; means for withdrawing gas from the gas space above the liquid in

said container and conducting said gas to said flow regulating means; and means incorporated in said flow regulating means for effecting the withdrawal of vapor only when the gauge pressure in said container is below a predetermined value, for permitting withdrawal of gas from said gas space when said pressure exceeds said predetermined value, and for insuring preferential flow of gas from said gas space when said pressure exceeds said predetermined value.

8. In gas dispensing apparatus comprising a container for liquefied gas having a gas space therein above the liquid; a heating coil in the liquid space of said container; vaporizing and superheating means; gas heating means; a liquid withdrawal conduit connecting the liquid space of said container to said vaporizing and superheating means; a superheated vapor conduit connecting said vaporizing and superheating means to one end of said heating coil; means connecting the gas space of said container to said gas heating means; a flow regulating device; a cooled vapor conduit conducting vapor from the opposite end of said heating coil to said device; a conduit connecting said gas heating means to said device; a single means incorporated in said device and responsive to the difference between the pressure in said container and the immediate atmospheric pressure, said single means operating to effect discharge of gas from said gas space only when said pressure difference exceeds a predetermined value; and an orifice in said device restricting the flow of said vapor through said device for insuring the preferential discharge of gas from said gas space when said pressure difference exceeds said predetermined value.

9. Gas dispensing apparatus including a container for liquefied gas and having a space above said liquefied gas for material in the gas phase; means for withdrawing from said container and heating liquefied gas; means for transferring heat from such heated gas to the liquefied gas within said container; and a tubular member surrounding such heat transferring means, said tubular member being supported by such heat transferring means in a vertical position and being in direct communication with the gas phase in the space above the liquefied gas in said container.

10. Gas dispensing apparatus including a container for liquefied gas having a space therein above the level of the liquefied gas for material in the gas phase; a tubular member having an open lower end extending into said liquefied gas

and enclosing a substantially vertical column thereof; means for heating said column of liquefied gas so as to gasify a portion thereof; and a single means for conducting the resultant gas from within said tubular member to the space above the level of the liquefied gas within said container, and for limiting the rise of the liquefied gas within said tubular member to a level below that of the liquefied gas within said container.

11. The method of dispensing gas material from a container of liquefied gas which comprises heating a definitely limited volume of said liquefied gas located within the main body thereof; confining the gas so produced to flow solely through said definitely limited volume to the space above the main body of said liquefied gas; and withdrawing said gas from said space.

12. The method of dispensing gas material from a container of liquefied gas which comprises substantially fully enclosing a vertically extending column of said liquefied gas within the main body thereof; withdrawing liquid from the main body of liquid; vaporizing said withdrawn liquid and superheating the resultant vapor; indirectly passing such superheated vapor only through said column of liquefied gas; reheating said vapor; and withdrawing gas from the space directly above said column of liquefied gas.

13. The method of dispensing gas from a container of liquefied gas which comprises withdrawing liquid from said container, vaporizing said withdrawn liquid and superheating the resultant vapor, transferring heat from such superheated vapor to a definitely limited volume of the main body of the liquid in said container; reheating said vapor; and withdrawing gas from the space directly above said definitely limited volume of liquid.

14. The method of dispensing gas from a container of liquefied gas which comprises substantially fully enclosing a vertically extending column of the main body of liquid in said container while providing for liquid communication between the bottom of said column and the main body of liquid; heating said column of liquid so as to gasify a portion thereof; conducting the resultant gas to the space above the level of the main body of liquid in said container, while limiting the rise of said column of liquid to a definite fixed level below that of the main body of liquid; and simultaneously withdrawing gas from said space.

GEORGE H. ZENNER.
